US0D1113050S

(12) **United States Design Patent** (10) **Patent No.:** **US D1,113,050 S**
(45) **Date of Patent:** **** Feb. 10, 2026**

(54) **WAGON CART**

(71) Applicant: **Min Zhang**, Hangzhou (CN)

(72) Inventor: **Min Zhang**, Hangzhou (CN)

(**) Term: **15 Years**

(21) Appl. No.: **29/984,148**

(22) Filed: **Feb. 17, 2025**

(51) **LOC (15) Cl.** **12-02**

(52) **U.S. Cl.**

USPC **D34/17**

(58) **Field of Classification Search**

USPC D34/12, 17, 23; D21/534, 536, 425

CPC .. B62B 3/02; B62B 3/10; B62B 3/007; B62B 1/12; B62B 1/22; B62B 5/0438; B62B 2205/30

(57) **CLAIM**

The ornamental design for a wagon cart, as shown and described.

DESCRIPTION

FIG. 1 is a front perspective view of a wagon cart, showing my new design;

FIG. 2 is a rear perspective view thereof;

FIG. 3 is a rear view thereof;

FIG. 4 is a front view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the wagon cart in a state of use; and,

FIG. 10 is a rear perspective view of the wagon cart in a folded state.

The broken lines in the drawings illustrate the portions of the wagon cart, which form no part of the claimed design.

1 Claim, 10 Drawing Sheets
